UNITED STATES PATENT OFFICE.

RALPH LOUIS SCHROEDER, OF OWENSBORO, KENTUCKY.

LIFE-SAVING BELT.

Application filed March 7, 1925. Serial No. 13,789.

This invention relates generally to life saving belts and aims to improve upon a structure such as is shown in my pending application filed in the United States Patent Office on the 20th day of August, 1924, assigned Serial No. 733,179 and allowed on the second day of February, 1925.

An important object of the invention is to provide means for inflating the belt when desired very quickly and easily by the use of highly compressed air.

The invention contemplates the carrying of a bottle of highly compressed air on the belt and having associated therewith means for puncturing the bottle and littering the air as it expands to a gas into the deflated belt for inflating the same so as to give the belt sufficient buoyancy to hold a person up in the water.

With the foregoing and numerous other objects in view as will appear as the description proceeds, the invention resides in certain novel features of construction, and in the combination and arrangement of parts as will be hereinafter more fully described and claimed.

In the drawing—

Figure 1 is a fragmentary elevation of a life saving belt with my improved structure mounted thereon.

Fig. 2 is an elevation of the container, and

Fig. 3 is a longitudinal section therethrough.

Referring to the drawing in detail, it will be seen that 1 designates a life preserver of the inflatable type which may be constructed as shown in my above identified co-pending application, or of any other suitable structure.

This inflatable member 1 is normally deflated and has extending therefrom a flexible inflating tube 2 which also may be of any desired structure. A pair of flaps 3 are sewed onto the member 1 and have apertures for receiving lacing 4 so that a container 5 may be mounted therein. Any other suitable means may be used for mounting this container.

My invention lies particularly in the container 5 and the elements about to be described. This container 5 is provided with a milled surface 6 or an otherwise roughened portion on its exterior surface so as to be held against slipping in the path 3. The container 6 is provided with an internally

threaded open end 7 and is adapted to receive a bottle 8 containing highly compressed air.

A closure 9 of suitable structure is provided in the bottle. A rubber gasket 10 is disposed about the end of the bottle 8 and is held in place by a bushing 11 rotatably engaged in a sleeve 12. This sleeve 12 is both externally and internally threaded so that it may be engaged in the threaded end 7 of the container 5. A member 13 is threaded into the sleeve 12 and is provided with a longitudinally extending bore 14 terminating at its outer end in a valve seat for receiving a check valve 15 which is held in place by a spring 16.

A cutter 17 is provided on the inner end of the member 13 and has a bore extending therethrough coincident with the bore 14. The tube 2 is engaged with the outer end 75 of the member 13.

By threading the member 13 into the sleeve 12 the piercing of the cutters 17 may be brought into engagement with the closure 9 of the bottle 8 for cutting a hole therein. When a hole is cut into the closure 9, the liquid air is free to expand and will rush through the bore 14, and through the tube 2 for inflating the member 1 without any further effort on the part of the person wearing the life preserver.

Inasmuch as the construction and operation of the invention will now be clearly understood without a more detailed description thereof.

It is desired, however, to point out that numerous changes in the details of construction, in the materials, and in the combination and arrangement of parts may be resorted to without departing from the spirit or scope of the invention as hereinafter claimed or sacrificing any of its advantages.

Having thus described my invention, what I claim as new is:—

1. As a new article of manufacture, a filling device for the tubes of life preservers and the like including a container, a bottle in the container for holding highly compressed air, a sleeve threaded into the container for holding the bottle therein, a member threaded in the sleeve and provided with a longitudinally extending bore, a cutter extending from the inner end of the member and provided with a bore coincident with the first mentioned bore whereby the member 100
- 105
- 110

may be threaded into the container for engaging the cutter with the bottle so as to pierce the same.

2. As a new article of manufacture, a filling device for the tubes of life preservers and the like including a container, a bottle in the container for holding highly compressed air, a sleeve threaded into the container for holding the bottle therein, a member threaded in the sleeve and provided with a longitudinally extending bore, a cutter extend-

ing from the inner end of the member and provided with a bore coincident with the first mentioned bore whereby the member may be threaded into the container for engaging the cutter with the bottle so as to pierce the same, and a check valve in the member for allowing the flow of the air from the bottle but preventing the flow thereof toward the bottle.

15

In testimony whereof I affix my signature.
RALPH LOUIS SCHROEDER.
